UNITED STATES PATENT OFFICE.

JACOB D. GRAYBILL, OF NEW ORLEANS, LOUISIANA, ASSIGNOR OF THREE-TENTHS TO WILLIAM W. BATTLE, OF SAME PLACE.

AERIAL MACHINE.

SPECIFICATION forming part of Letters Patent No. 592,704, dated October 26, 1897.

Application filed May 26, 1896. Serial No. 593,173. (No model.)

To all whom it may concern:

Be it known that I, JACOB D. GRAYBILL, of New Orleans, in the parish of Orleans and State of Louisiana, have invented a new and useful Improvement in Aerial Machines, of which the following is a specification.

My invention is an improved machine for aerial navigation; and the invention consists in certain novel constructions, combinations, and arrangements of parts, as will be herein-after described, and pointed out in the claims.

In the drawings, Figure 1 is a top plan view, Fig. 2 a side view, and Fig. 3 a cross-section on about line 3 3, Fig. 2, of a machine embodying my improvements. Fig. 4 is a detail horizontal section on about line 4 4, Fig. 3. Fig. 5 is a detail view of the devices for shifting the cross-shaft, and Fig. 6 represents the lever-lock in detail.

In carrying out my invention I provide a body A in the form of a gas-holder, whose frame is composed of aluminium tubing and which may be covered with aluminium or other light material. The tubing a may be filled with compressed gas to lighten the weight of said tubing. In practice the gas-holder may be made in the form shown or in any other suitable shape desired. Between the ends of the holder A, I arrange the basket 30 or car C, preferably formed in the under side of the holder, so that its chambers in front and rear of the car can be connected by a passage A'.

An air-chamber D separates the ends and top of the car from the gas-holder. This air-chamber is employed to assist in controlling the buoyancy of the machine in raising and lowering it or in a light and strong breeze. By pumping air into this chamber I overcome the amount of gas used to raise the machine, thereby causing the machine to descend. The air-chamber also serves to prevent the persons or articles in the car from being affected by the gas should any escape.

At the rear of the gas-holder I provide a rudder E, which may be turned from side to side, and this rudder may be worked in the same manner as the rudder of a boat and by the devices shown or other suitable constructions, as may be desired.

The operating mechanism is preferably

supported in the car, and gas, air, or electric engines may be employed for driving the same, while an ordinary air-pump can be used to pump air into the air-chamber. The engine shown is that known as a "Weber gasolene-engine," but, manifestly, any form or pattern of engine may be used if desired.

The operating mechanism comprises a cross-shaft F, which is movable longitudinally in its bearings G and is geared by wheel f with the drive-gearing. A lever H is pivoted at h and is forked at one end to engage on opposite sides of the wheel f, so it may be operated to set the shaft F longitudinally and in either direction. On this shaft F are secured the ball-balanced crank-arms I, having the blocks i, provided with openings i', through which the lever-arms J of the wings pass, such arms J constituting lever devices by which to operate the wings. The wings K are supported by the lever-lock on which the arms of the wings move up and down and back and forth, the locks being so adjusted as to allow the wings to be set in any position. These wings when not used for propelling the machine can be used as side sails. By means of the lever H the shaft F can be set endwise, thereby giving the wing on the side toward which it is moved a greater sweep than the opposite one, and vice versa when the lever is reversed.

The shaft L, geared with the cross-shaft F, is shown provided with crank-handles, by which it may be turned; but I do not desire to be limited to any particular means for operating the cross-shaft or to any particular devices for connecting the operating means with such shaft.

The arms J of the wings are supported in the lever-locks L¹. (Best shown in Fig. 6.) These lever-locks consist of the levers L', pivoted at l' and universally jointed at l to the locks L², in which are pivoted the rocking shafts L³, in which the arms J of the wings are held.

The levers L' may be moved on their pivots to vary the angle of the wings or to set such wings to position for sailing, a pawl M and rack M' being provided by which to hold the lever in any desired adjustment. It will also be seen that the wings may be adjusted to

position to cause the machine to ascend or descend; also, that the wings may be adjusted independently and so aid in guiding the machine to one side or the other.

5 It will be seen that the air or vacuum chamber has no communication whatever with the gas or buoyancy chamber. When the latter chamber is once filled, no gas is withdrawn or condensed in order to ascend or descend. 10 To descend, I simply pump air into the air-chamber to overcome the buoyancy. This can be done at any height, air and gas always having the same relative difference in weight.

15 In practice I provide a hydrogen-gas chamber that will hold ten thousand cubic feet of gas. Into this chamber I put nine thousand cubic feet of gas, leaving one thousand cubic feet of space for expansion. The nine thousand cubic feet of gas give me a buoyancy of six hundred and twelve pounds at sea-level. If my ship complete weighs two hundred pounds, I still have a buoyancy of four hundred and twelve pounds. Taking from this 20 the weight of two men, each one hundred and seventy-five pounds, and I have left a buoyancy of seventy-two pounds. Thus if my air-chamber has space to receive but four hundred cubic feet of air I have air-space enough 25 to overcome four times seventy-two pounds of buoyancy. Then if seventy-two pounds of buoyancy takes us higher than we wish to go, by simply opening the valve in the air-pump we allow air to pass into the air-chamber until we have checked our upward flight. Then 30 the wings can be used to propel the car in any desired direction.

Having thus described my invention, what I claim as new, and desire to secure by Letters Patent, is—

40 1. An aerial ship comprising a gas-holder, a car located within the framework of said gas-holder, an air or vacuum chamber protecting the car from gas on front, back and top substantially as shown and described.

45 2. In an aerial machine, the combination

of the shaft, the wings, the arms J connected with the wings and universal joints between the said arms and the shaft and supporting devices for said arms J whereby the wings 50 are caused to move similarly to an oar in rowing all substantially as set forth.

3. The combination of the wings, the cross-shaft movable longitudinally in its bearings, the lever by which to effect the said movement, the wings the arms connected with the wings and universal joints between said arms and the shaft substantially as set forth. 55

4. In an apparatus substantially as described the combination of the lever-lock consisting of the lever and the lock jointed thereto the wing having its arm held by said lock and the operating devices connected with said arm substantially as shown and described. 60

5. The combination of the pivoted lock-lever, means whereby said lever may be held in any desired adjustment, the lock jointed to said lever, the wing having its arm held in said lock and the operating devices connected with said arm substantially as shown and described. 70

6. The combination of the cross-shaft having crank-arms the wings having their arms connected with the cranks of said shaft and adjustable supports for said wing-arms substantially as shown and described. 75

7. The combination of the cross-shaft having cranks, the wings having their arms connected with said cranks the lever-locks supporting the opposite wing-arms and adjustable independently and means for holding said lever-locks in any desired adjustment. 80

8. In a machine substantially as described, a non-collapsible wing made approximately V shape in cross-section and arranged with the point or apex forward all substantially as and for the purpose shown and described. 85

JACOB D. GRAYBILL.
